TUNER CONSTRUCTION

Innokent N. Vorie, Elma, N. Y., assignor to
Colonial Radio Corporation, Buffalo, N.Y.

Application August 8, 1945, Serial No. 609,593

5 Claims. (Cl. 171—242)

1

This invention relates to tuner construction, and more particularly to such construction particularly adapted for use in ultra high frequency apparatus, such as television and frequency or amplitude modulated radio equipment, where the frequencies dealt with are measured in terms of megacycles rather than kilocycles.

It is an object of this invention to provide a tuning construction for the purposes described, in which the equipment is extremely compact.

It is a further object of this invention to provide such apparatus in which a relatively large range may be covered with a high Q.

It is still a further object of this invention to provide apparatus of the class described in which small changes in tuning frequency may easily be made without excessively small manual movements.

It is a further object of this invention to provide such apparatus employing permeability tuning, which is free from the defects heretofore characteristic of such tuning.

It is a further object of this invention to provide such apparatus, which is free from microphonic properties.

It is a further object of this invention to provide tuning apparatus of the class described which is generally superior to that heretofore known and used for the purpose.

Still other objects and advantages of my invention will be apparent from the specification.

The features of novelty which I believe to be characteristic of my invention are set forth with particularity in the appended claims. My invention itself, however, both as to its fundamental principles and as to its particular embodiments, will best be understood by reference to the specification and accompanying drawing, in which

Fig. 1 is a side elevation of a tuner in accordance with my invention, with the pointer displaced 90° from its true position (for convenience of illustration),

Fig. 2 is a front elevation thereof with the coil omitted for convenience of illustration, and

Fig. 3 is a section on lines 3—3 of Fig. 1.

It is generally recognized that permeability tuning has certain advantages when applied to apparatus operated in the present broadcast frequencies. However, in attempting to apply permeability tuning principles to ultra high frequencies, certain difficulties are encountered.

In the ordinary form of permeability tuner, a comminuted iron core is moved lengthwise within a coil, thereby changing its resonant frequency. When such construction is attempted to be ap-

plied in the ultra high frequency bands; for instance, to provide a tuner to cover 84 megacycles to 102 megacycles, it will be found that the inductance is of the order of 0.1 to 0.05 microhenry, depending on the minimum distributed capacity of the circuit, and a coil having such inductance is quite small, having only a few turns; if the usual permeability core is attempted to be used, the axial movement of the core to cover the band will not be substantially over $\frac{1}{8}$ ".

It is apparent that to permit selection of stations with such a small movement of the core extreme accuracy of parts is required, and some relatively high step-down ratio mechanical transformer must be employed between the tuning knob and the core, all of which have made permeability tuning for such applications impractical or uneconomical.

According to my invention, I provide a tuner which will operate over the range specified without requiring any such arrangements, and in which the full 180° of the manual tuning knob is available for tuning and may be applied directly to the permeability core. This result is obtained by utilizing and combining in the tuner the principles of permeability tuning, of short-circuited turn tuning and the 180° coupler.

Instead of moving the permeability core lengthwise within the coil, I prefer to rotate the core instead, and to provide the coil wound with the plane of its turns at an angle of 45° with the axis of the core, and I inlay or form within the core a short-circuited turn of a good conductor, such as copper or silver, of the same width as the coil, and likewise mounted with its plane at an angle of 45° to the core axis.

Rotation of the core, as will be understood, through a complete turn will cause the core to pass through two position, 180° apart, in one of which the short-circuited single turn is perpendicular to the coil windings and, therefore, is of minimum effect, permitting the iron core to exert its full effect, and increasing the inductance of the coil to a maximum.

At a position 180° from this, the short-circuited turn is in the plane of the coil and directly within it at all points, thereby reducing the inductance to a very low value. At positions intermediate these two, the inductance of the coil will have an intermediate value.

Referring now more particularly to the drawing, the coil may be formed as shown at 10, and in this instance I have indicated a coil comprising 55 1 1/2 turns of copper wiring or tubing. This is

fixedly mounted around core 11, which is free to rotate within the coil.

The core is preferably formed of any suitable mixture of powdered iron and a binder, as will be understood by those skilled in the art, and carries upon it single short-circuited turn 12, which may be copper or silver, the width of which is equal to the width of the coil at its widest point, and the coil, core, and turn 12 are so positioned that at some point in the rotation of the core, turn 12 lies directly under coil 10 and at another point 180° therefrom it extends at right angles thereto.

The core may be mounted in pulley 13 at one end, and pulley 13 may carry shaft 14 extending through frame 15, which carries upstanding end portions 16 and 17 to receive and support the core. The other end of the core may be secured for rotation by ball 18, fitting in depressions in core 11 and in mounting screw 19, which extends inwardly through frame portion 16. The coil may be supported by passing its ends through openings in bracket 20 of insulating material secured between end plates 16 and 17. Dial 25, suitably calibrated, may be carried on end plate 17, and pointer 26 carried on shaft 14 for reading dial 25.

Rotation may be effected by a knob on shaft 14, which knob may be turned directly by the operator, or if desired, an offset drive may be employed utilizing knob 21 mounted on shaft 22 extending through end plate 17 and terminating in driving pulley 23, from which belt 24 or cord drive may extend to driven pulley 13 carrying the core.

With such an arrangement and with a minimum capacity in the circuit of 40 micro-microfarads, I have been able to cover a range of 80-103 megacycles with a Q of 170 and 110 respectively.

In the specification I have explained the principles of my invention and the best mode in which I have contemplated applying those principles, so as to distinguish my invention from other inventions; and I have particularly pointed out and distinctly claimed the part, improvement, or com-

bination which I claim as my invention or discovery.

While I have shown and described certain preferred embodiments of my invention, it will be understood that modifications and changes may be made without departing from the spirit and scope thereof, as will be clear to those skilled in the art.

I claim:

- 10 1. In tuning apparatus, in combination, a core of comminuted paramagnetic material, longitudinally fixed but free for rotation, a coil surrounding said core, said coil having the plane of its windings disposed at an angle to the axis of said core, and said core having a short-circuited turn of good conducting material encircling said core, and having its plane disposed at an angle with respect to the axis of the core.
- 15 2. The combination claimed in claim 1, in which said short-circuited turn is positioned on said core within the limits of said coil projected perpendicularly upon the core.
- 20 3. The combination claimed in claim 1, in which the angle between the plane of the coil windings and the axis of the core, and the plane of the short-circuited turn and the axis of the core is 45°.
- 25 4. The combination claimed in claim 1, in which the short-circuited turn is inlaid in the material of the core.
- 30 5. The combination claimed in claim 1, in which the surface of the short-circuited turn lies substantially flush with the surface of the cylinder.

Certificate of Correction

Patent No. 2,422,995.

June 24, 1947.

INNOKENT N. VORIE

It is hereby certified that error appears in the printed specification of the above numbered patent requiring correction as follows: Column 2, line 39, for "186°" read 180°; and that the said Letters Patent should be read with this correction therein that the same may conform to the record of the case in the Patent Office.

Signed and sealed this 30th day of September, A. D. 1947.
